Primary Examiner — Patricia A Palasik(57) **CLAIM**

The ornamental design for a delta robot, as shown and described.

DESCRIPTION

FIG. 1 is a top, front and left side perspective view of a delta robot showing our new design;

FIG. 2 is a top, front and right side perspective view thereof;

FIG. 3 is a bottom, rear and left side perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of portion 10 in FIG. 1;

FIG. 11 is an enlarged view of portion 11 in FIG. 3;

FIG. 12 is a top, front and left side perspective view showing the delta robot in a use state; and,

FIG. 13 is a top, front and right side perspective view showing the delta robot in a use state.

The broken lines in the drawings illustrate portions of the delta robot which form no part of the claimed design.
